UNITED STATES PATENT OFFICE.

BENJAMIN WOLHAUPTER, OF NEW ROCHELLE, NEW YORK.

ADJUSTABLE RAIL-ANCHOR.

1,353,204.

Specification of Letters Patent. Patented Sept. 21, 1920.

Application filed May 15, 1917. Serial No. 168,822.

To all whom it may concern:

Be it known that I, BENJAMIN WOLHAUPTER, a citizen of the United States, residing at New Rochelle, in the county of Westchester and State of New York, have invented certain new and useful Improvements in Adjustable Rail-Anchors, of which the following is a specification.

This invention relates to a novel and practical construction of rail anchor to prevent creeping of railway rails. In devices of this character it is desirable to provide a construction having few and simple parts that may be easily and economically manufactured and readily assembled when applying the device in track.

The present invention has these important characteristics and features besides possessing the distinct and practical advantage of being readily applicable to rails of different size, so that the device may be applied with equal facility to rails having rail bases of different widths, without in any way impairing or affecting the efficiency of the same as an anchoring device to secure and firmly hold the rail upon a tendency thereof to move or creep in a longitudinal direction.

In the attainment of the above objects, the present invention particularly has in view a rail anchoring device having no working or movable parts such as springs, moving cams or equivalent mechanical elements, but simply consisting of two principal members, which are brought into secure and operative relation upon application of the device to the base flanges of the rail, and which members are relatively adjustable so as to be adaptable to rail bases of different widths.

With these and many other objects in view which will readily appear to those familiar with the art as the details of the invention are better understood, the latter consists in the novel construction, combination, and arrangement of parts hereinafter fully pointed out, illustrated, and claimed.

The essential features of construction are necessarily susceptible of modification without departing from the spirit or principle of the invention, but a preferred and practical embodiment thereof is shown in the drawings, in which

Figure 1 is a perspective view of a two part rail anchor constructed in accordance with the present invention, and illustrating

its application to the flanges of a rail adjacent a tie.

Fig. 2 is a top plan view showing more clearly the relation of the device to the rail flanges and the adjacent tie.

Fig. 3 is an elevational view, partly in section, illustrating the application of the device to a rail, and showing the detachable rail engaging locking clip in the position which it occupies when about to be driven onto one of the rail flanges, and over the leverage arm of the device, by means of a spike maul or other implement.

Fig. 4 is a view similar to Fig. 3 illustrating the anchor in its locked position upon the rail.

Fig. 5 is a view similar to Fig. 4 showing the adaptability of the anchor to a rail base of smaller size.

Fig. 6 is a modification illustrating a supplemental holding means that may be utilized for additional security in retaining the locking clip engaged with the tension bar and with the rail flange.

Fig. 7 is a similar view showing another modification illustrating another form of holding means that may be employed to secure the locking clip in its proper relation to the tension bar and to the rail flange.

Similar reference characters designate corresponding parts throughout the several figures of the drawings.

The rail anchor of the present invention may be embodied in different forms of construction without affecting the essential principles thereof, but in embodiments shown in the drawings may be, and preferably is, constructed of two principal parts or members. In this form of construction, one of these parts is designated by the reference letter A and the other of said parts is designated by the reference letter B.

The part or member A of the improved rail anchor essentially consists of what may be termed a tension bar, designated by the numeral 1 and formed at one end with a preferably integral fixed rail engaging clip 2, which is adapted to have a wedging fit and engagement over and upon one of the rail flanges of the rail to which the device is applied. This rail engaging clip 2 at one end of the tension bar 1 is a fixed element of the bar 1 as distinguished from the detachable or removable member B of the device, and is made by looping or bending one

end of the bar 1 inwardly, producing an upper jaw 3 and a spring loop 4 combining with the jaw 3 to provide for a spring clamping action and forming the flange receiving socket 5 which accommodates the tapering flange of the rail. It will also be observed that the said socket 5 is of a sufficient depth to provide the necessary clearance and adjustment for the clip to adapt itself to the rail flange when driven thereon. Furthermore, since the two elements 3 and 4 of the clip 2 occupy a divergent relation with respect to each other, the clip acts as a wedge, when driven upon the rail flange, to wedge itself tightly thereon, and thereby firmly grip one of the flanges of the rail. In this connection, it is to be further noted that the upper jaw 3 of the fixed rail engaging clip 2 is preferably of a conformation that will adapt itself for a firm and gripping engagement with the upper side of the rail flange, while the loop 4 of the clip has a clearance from the underside of the rail flange and from the rail base in order to admit of the leverage action which takes place in the application and locking of the tension bar.

In reference to the features of construction involved in the leverage action above referred to, the tension bar 1, including its terminal clip 2, is preferably made of a suitable grade of spring steel, and is also preferably longitudinally bowed to provide an intermediate crowning or arched portion 6 constituting an intermediate upstanding fulcrum element, that has a binding and fulcruming engagement against the bottom of the rail. At the side of the fulcrum element 6 opposite the side of the bar carrying the clip 2, the said bar is formed with a leverage arm 7, having a permanent clearance from the underside of the rail and preferably provided with an inclined locking portion 8 and at its extremity with a guide tongue 8^a formed at its underside with a guiding bevel 9.

The leverage arm 7 of the tension bar 1 cooperates with the other part or member B of the device. The said part or member B of the anchor consists of a one-piece detachable rail-anchoring locking-clip. This locking clip is provided with an upper inclined jaw 10, and a lower socket element 11, the latter underlying the rail base and having a divergent relation to the upper jaw 10, so as to form a complete clip which wedges upon the rail flange opposite the fixed rail engaging clip 2. According to the present invention, the socket element 11 is formed with a keeper opening 12 lying substantially parallel with the rail base and adapted to receive and hold therein the inclined portion of the leverage arm 7 of the tension bar. At the bottom of the keeper opening 12, the socket element 11 is formed with an inclined

holding seat 13 adapted to be engaged by the portion 8 of the leverage arm 7. At one side of the holding seat 13, at the inner side of said element 11, is the guiding bevel 14, which cooperates with guide tongue 8^a, 70 of the leverage arm.

From the foregoing description and the drawings, it will be apparent to those familiar with this subject that the improved anchor may be applied to a rail, adjacent a tie with readiness and facility. When applying the device, the act of driving the fixed rail engaging clip 2 onto one of the rail flanges causes a distortion of the parts which is accommodated, under strong spring pressure, by the opening of the spring loop 4. This operation results in bringing the fulcrum 6 into firm binding and fulcruming engagement with the underside of the rail whereby the clip 2 is caused to become firmly wedged and bound upon the rail flange. This wedging action of the clip 2 is materially increased and rendered thoroughly effective, as a rail holding means, upon the application of the locking clip B. 85 This locking clip operates as a separate holding member for the tension bar of the device and represents one form of holding member, that is to say, a holding member which engages the tension bar and the rail flange. In the use of this form of holding member, it will be noted that the same is slipped over the guide tongue 8^a and driven home over one of the rail flanges by a maul or other implement, or the operation might 90 be reversed by first applying the locking clip B to one rail flange and then driving the other part of the device into position. However, assuming that the locking clip is the second step in the operation of fastening 105 the anchor in place, the said clip, in passing to its position over the rail flange, first slides over the guiding bevel 9 at one extremity of the tension bar until the seat 13 reaches and becomes engaged with the inclined underside of the inclined locking portion 8 of the tension bar or leverage arm 7 of the device. With the parts in this position, the said leverage arm 7 in effect, becomes locked upon the seat 13 and is held thereby under strong tension and securely restrained from accidental displacement. The said action is involved and the same effect produced in the application of the device to rails of varying sizes as will be apparent from Figs. 4 and 5 of the drawings showing the anchor applied to rails of different sizes.

By way of illustrating the range of modification that may be resorted to in carrying out the invention there is shown in Fig. 6 of the drawings a form in which the locking action of the leverage arm 7 binding on the holding seat 13 may be supplemented. That is to say, according to this suggested modi- 125 130

ification the end portion of the leverage arm is threaded as indicated at 15 to receive a fastening nut 17 binding against the outer side of the detachable locking clip B. This 5 construction will provide additional security in operatively securing the locking clip engaged with the tension bar and with the rail clamp.

Also a further exemplification of the invention is afforded by the modification illustrated in Fig. 7, wherein a very effectual locking action may be obtained by providing the leverage arm adjacent its terminal tongue 8^a with an abrupt or sharply inclined locking portion 8^b, and by forming the holding seat 13 on the corresponding abrupt inclination. A construction of this character in effect produces a locking shoulder adjacent the free end of the leverage arm 7 20 which springs into firm locking engagement with the seat 13 when the parts are brought into operative relation.

Without further description, it is thought that the many features and advantages of 25 the present invention will be readily apparent, and it will, of course, be understood that various changes in the form, proportion, and minor details of construction may be resorted to without departing from the 30 spirit of the invention or scope of the appended claims.

I claim:

1. A rail anchor comprising a spring bar having at one end a fixed rail engaging clip 35 and its opposite end portion standing free from the rail bottom, and a detachable clip transversely slidable upwardly on the

inclined base of one rail flange and also having a slidable engagement with the free end of the bar to place the same under tension. 40

2. A rail anchor comprising a spring bar having at one end a fixed rail flange engaging clip while its opposite end portion is disposed at such an angle as to stand free of the rail bottom before and after application, and a detachable clip for slidably engaging with the free end of the spring bar and also with the upper face of one rail flange. 45

3. A rail anchor comprising a bar having 50 at one end a fixed rail engaging clip and its other end having a permanent clearance from the under side of the rail, and a detachable rail engaging clip having a sliding and holding engagement with the bar and 55 slidably engaging the upper side of the rail flange whereby the bar is forced into binding engagement with the rail through the sliding of the clip along the top inclined surface of the rail. 60

4. A rail anchor comprising a spring bar having at one end a fixed rail flange engaging clip while the opposite end thereof is arranged to stand free of the rail bottom, and a detachable clip having an opening for 65 receiving the free end of the spring bar and also having an inclined face for engaging the upper side of the rail flange.

In testimony whereof I hereunto affix my signature in the presence of two witnesses. 70
BENJAMIN WOLHAUPTER.
